[57] CLAIM

The ornamental design for a portable work light or the
like, as shown and described.

DESCRIPTION

FIG. 1 is a perspective view of a portable work light or
the like showing my new design;

FIG. 2 is a side elevational view thereof;

FIG. 3 is a top plan view thereof;

FIG. 4 is an opposite side elevational view thereof;
FIG. 5 is a side elevational view thereof as seen from
the left of FIG. 4, the view seen from the right being a
mirror image;

FIG. 6 is a bottom plan view thereof.
